UNITED STATES PATENT OFFICE

FREDERICK A. KOLSTER, OF SAN JOSE, CALIFORNIA, ASSIGNOR TO FEDERAL TELEGRAPH COMPANY, OF SAN FRANCISCO, CALIFORNIA, A CORPORATION OF CALIFORNIA

RADIO RECEIVING SYSTEM

Application filed October 2, 1923. Serial No. 666,060.

This invention relates to a system for receiving radio frequency electrical energy, and more particularly to a scheme whereby the desired signals may be selected from other interfering signals, and amplified. This I accomplish by the aid of a selector, which is arranged with respect to the system to provide a path of relatively low impedance for the interfering signals. The amplifiers being in a separate path are to a great extent 10 left unaffected by the interfering signals.

Such an arrangement of circuits has been described and claimed in my Patent No. 1,717,455, granted June 18, 1929, and entitled: 15 "Selector and receiver for radio frequency energy". It is one of the objects of my invention to improve the amplifying qualities of this system where amplifiers of the electron emission type are utilized.

It is another object of my invention to 20 make it possible to receive and select signals on short wave lengths, such as broadcasting, in a manner that will permit the amplifying electron emission tubes to be operated at their 25 maximum amplifying power.

My invention possesses other advantageous features, some of which with the foregoing, will be set forth at length in the following description, where I shall outline in full that 30 form of the invention which I have selected for illustration in the drawing accompanying and forming part of the present specification. Although I have shown in the drawing but one embodiment of my invention, I 35 do not desire to be limited thereto, since the invention as expressed in the claims may be embodied in other forms also.

Referring to the drawing:

The single figure is a wiring diagram of a 40 radio receiving system embodying my invention.

In the present instance I have illustrated my invention as applied to a radio receiving system using a plurality of stages of radio 45 frequency amplifiers 1, 2, and 3 of the electron emission type. However, it is evident that the principles disclosed may be readily applied to audio frequency amplifiers or to a combination of audio and radio frequency 50 amplifiers; although the invention is perhaps

most advantageously utilized in connection with radio frequency amplification.

The oscillations to be amplified are in this instance absorbed from an energy transmitting medium in a circuit such as the antenna 4, loading coil 5, variable condenser 6, and a ground connection 7. The first stage of amplification through the three-electrode device 1 is secured by coupling the filament-grid circuit to the antenna circuit, as for example, by the aid of coil 8 inductively associated with the antenna coil 5. In order to secure the maximum effect, a tuning condenser 9 is bridged across the coil 8, the terminals of which are respectively connected to the grid 10 and an electron emitting element 11 of the amplifier 1. The circuit between the grid 10 and the element 11 is the input circuit for the amplifier, the operation being dependent upon the variations, in accordance with the signal amplified, in the electromotive force between these two elements. These variations are amplified in the output circuit for the amplifier 1, which circuit includes a cold electrode or plate 12, enclosed within the amplifier tube, an impedance device 13, a plate battery 14, and the element 11. Since such amplifying devices are well known, it is not at all necessary to enter into further detail as regards the theory of operation. It may be mentioned however that the electron emitting element 11 is usually in the form of a filament which is heated to a temperature sufficient to cause it to emit electrons. For producing the heating effect, a source of electrical energy, such as the battery 15, may be utilized.

The amplified signals through the translating device 13 are passed through a second amplifier stage; for this purpose the second thermionic amplifier 2 may be used. This amplifier operates in substantially the same manner as the amplifier 1. It is however necessary to couple the two tubes 1 and 2, and my invention is most concerned in the manner in which this is accomplished. It has been shown that in order to secure a high degree of amplification, the output circuit for the tube should have an impedance or a resistance comparable with that of the tube itself, furthermore, the coupling between 10

this circuit and the input circuit of the succeeding tube should be as close as possible, so as to utilize the energy in this output circuit to the maximum extent. In order to fulfill these conditions, the device 13 in the output circuit of amplifier 1 is shown as having a very large impedance, which may be either a very large resistance or a very large inductance, or a combination of these two quantities. Furthermore, the amplifier 2 is directly coupled to the output circuit of amplifier 1, preferably by means of the lead 16 and the stopping condenser 19 connecting the plate terminal of the high impedance 18 to the grid 17 of the amplifier 2. The filament 18 for this amplifier is shown as connected to the heating battery 15. The battery connections also serve as a direct coupling between the two amplifiers 1 and 2. The stopping condenser 19 is inserted in lead 16 to prevent the high potential of the plate battery 14 from being impressed upon the grid 17.

Although the mode of coupling just described has been proposed heretofore, it has been found to be impracticable or unsatisfactory for short wave-length amplification. This is probably due to the effect produced by the inter-electrode capacity of each of the coupled tubes. But from whatever cause, it has nevertheless been found that the desirable effects of a high impedance in the output circuit and of a close tandem coupling are not attainable for short wave operation. My invention aims to over-come this defect, by connecting a selector such as 20 across the grid 17 and filament 18 of the coupled tube. This selector includes preferably an inductance coil 21 and a variable condenser 22 in parallel. The condenser 22 is adjusted to such a point that the selector circuit between the grid and filament has substantially infinite impedance for energy of the selected frequency which it is desired to amplify. Thus no substantial amount of signaling energy can flow in this circuit, which then has a very high impedance to currents at or near the frequency of the radio signals which are to be amplified. To secure this result, either the condenser 22 or the inductance 21 is adjusted so that at this frequency the inductive reactance of coil 21 is equal to the capacitive reactance of condenser 22. Under such circumstances whatever current of the tuned frequency may be flowing in the coil 21 has its exact counterpart in the current flowing in condenser 22, since these elements have the same electromotive force impressed across them. Thus so far as the external circuit is concerned, these two currents cancel each other, and none can flow through the selector, although there may be a circulatory current in the closed path formed by the elements 21 and 22.

65 The operation of the selector 20 to by-pass

interfering signaling energy has been detailed at length in the application heretofore identified. It is accordingly unnecessary to discuss this operation here. Its new function in the combination disclosed I believe is to alter the influence of the capacity between the electrodes of the tubes, whereby the detrimental effects heretofore noted are overcome. Furthermore, the selector 20 allows the potential of grid 17 to be controlled with respect to the filament 18.

In case a third stage of amplification is desired, a third tube 3 is used, which is coupled to tube 2 in a manner entirely similar to that already described. In this instance, however, instead of using a coil such as 13 in the output circuit of amplifier 2, a non-inductive high resistance 23 may be utilized, which provides substantially similar effects. A wave selector 24 is again used between the grid and filament of tube 3 for the same purpose as described heretofore. As many stages of radio frequency amplification may be further added as desired, utilizing the coupling system constituted by non-inductive high resistance 23 and selector circuit 33. It is however considered unnecessary to disclose these further stages, since obviously they may be added to the system in accordance with the teachings already outlined. The devices 13, 23 and 33 each constitute an untuned element having a high radio frequency impedance and may be formed by any equivalent element which possesses a high radio frequency impedance characteristic.

In order to detect the signals, there may be provided a three-electrode thermionic device 25, having a heated filament 26, grid 27, and plate 28. The grid 27 is connected to the output circuit of amplifier 3 through the usual grid condenser 29 and grid leak 30. The filament 26 may also be connected in any appropriate manner with the amplifier circuit. The output circuit of detector 25 includes the plate 28, a translating device such as phones 31, and a battery 32. A selector 33 may also be connected across the grid 27 and filament 26 of the detector 25, so as to shunt whatever interfering energy there may be present in the output of amplifier 3. The coupling between the output circuit of tube 3 and the detector tube 25 is effected by the non-inductive high resistance 35 similar to the non-inductive resistance 23 between the tubes 2 and 3. As indicated by the dotted lines 34 and the legend, all of the selectors 20, 24 and 33 may be arranged to have a common control, so that they may be simultaneously adjusted by a single operation. This feature is of importance, since thereby the adjustments may be very quickly made.

It is of course possible to provide audio frequency amplifiers with this circuit. Since the application of these amplifiers presents

no essentially new features they have been omitted.

It is evident that from the foregoing disclosure the advantages of close coupling between the tubes by the aid of a high impedance in the output circuits may be obtained for short wave operation when use is made of my invention.

I claim:

1. A cascade radio frequency amplifier adapted to selectively amplify energy over a substantial range of radio frequencies comprising at least two electron emission tubes each having input and output circuits, an untuned element having a high radio frequency impedance coupling together the output of the first tube with the input of the second and having a high impedance throughout said range of frequencies, a similar high radio frequency impedance coupling together the output of the second tube with the input of a translating circuit, a variable selector connected in parallel with the input of the second tube, and a similar selector in parallel with the input of each electron tube circuit, each selector comprising an inductance element and a condenser element in parallel with the inductance element of each selector, one of said elements being simultaneously variable by operation of a single control whereby the system may be tuned for any one frequency within said range. 90
2. A cascade radio frequency amplifier adapted to selectively amplify energy over a substantial range of radio frequencies comprising at least two electron emission tubes each having input and output circuits, an untuned element having a high radio frequency impedance over said range of radio frequencies for coupling together the output of the first tube with the input of the second tube, a similar high impedance coupling together the output of the second tube with a translating circuit, a variable selector connected in parallel with the input of the second tube, a similar selector connected in parallel with the input of said translating circuit, each selector comprising a variable condenser in parallel with a fixed inductance, and a single control for varying the respective capacitances of said condensers in unison whereby the system may be varied to amplify any selected frequency within said range. 105
3. A radio receiving system adapted to selectively receive energy over a substantial range of radio frequencies comprising at least two electron emission amplifying tubes each having input and output circuits, an untuned element having a high radio frequency impedance for coupling the output of the first tube to the input of the second tube, an independent radio frequency impedance for coupling the output of the second tube to the input of a translating circuit, means includ- 110
- ing a variable condenser for selectively tuning the input of the second tube, means including a second variable condenser for selectively tuning the input of the translating circuit, independent inductances connected in shunt with each of said variable condensers, a common control for varying said condensers in unison, and means including an independently variable condenser for selectively coupling the input of the first tube to a source of radio frequency energy. 115
- In testimony whereof, I have hereunto set my hand.
